UNITED STATES PATENT OFFICE.

THOMAS DAVIS, OF VANCOUVER, BRITISH COLUMBIA, CANADA.

CROSS-TIE.

1,141,444.

Specification of Letters Patent. Patented June 1, 1915.

Application filed July 30, 1913. Serial No. 782,147.

To all whom it may concern:

Be it known that I, THOMAS DAVIS, a subject of the King of Great Britain, residing at Vancouver, in the Province of British Columbia and Dominion of Canada, have invented certain new and useful Improvements in Cross-Ties, of which the following is a specification.

This invention relates to improvements in railway ties and has for its object to provide a combined sleeper and rail chair structure designed to be formed of metal and constructed and arranged to insure anchorage of the rails, not only to their proper gage, but to also prevent spreading of the rails.

One of the special features of my invention resides in structural features whereby any movement of the rails from their gaged position will be resisted by locked metallic structural parts.

A further feature of the improvement consists in the novel construction whereby removal and replacement of the rails may be readily effected.

The invention includes other features of novelty and construction which will be more fully described in connection with the accompanying drawings and which will be more particularly pointed out in and by the appended claims.

In the drawings:—Figure 1 is a cross sectional view of two rails mounted upon and secured to one form of the device of my invention. Fig. 2 is a plan view of the structure shown in Fig. 1. Fig. 3 is a sectional view on line 3—3 of Fig. 1. Fig. 4 is a sectional view on line 4—4 of Fig. 1. Fig. 5 is a longitudinally vertical sectional view of one end portion of my improved sleeper. Fig. 6 is a perspective view of one of the movable rail shoes.

Like characters of reference designate similar parts throughout the different figures of the drawings.

Referring to the form illustrated, 1 designates a sleeper which is designed to be formed of metal and which is of channeled cross section having outwardly extending flanges 2. While I prefer that the sleeper, like the remainder of the structure, should be made of metal, it will be understood that the sleeper may be formed of concrete or other suitable material if desired.

Chairs for the rails are shown consisting of a single piece of material which may be in the form of a flat plate 3 adapted to be

bolted or otherwise secured to the flanges 2, and shown extending throughout the length of the sleeper 1. The chair plate 3 is provided with preferably integrally formed 60 shoes 4 adapted for engagement with the outer faces of the rail webs and flanges. The rails which are designated at 5, rest upon the chair plate 3 as shown in Fig. 1, and I provide movably mounted shoes 6 and 7 for 65 engaging the inner sides of the rail flanges and webs. The inner shoes 6 and 7 are slidably mounted upon the chair plate 3, and as illustrated in Fig. 4, the chair plate 3 is provided with a depressed and preferably dove-tail grooved top portion 8, which extends inwardly toward the longitudinal center of the structure for a relatively considerable distance. As shown, said dove-tail grooved top portions 8 terminate in an enlarged portion 9, as clearly shown in Fig. 2. The shoes 6 and 7 are provided with dove-tailed projections 10 and 11 adapted to fit the dove-tailed grooves of the rail plate 3. The central enlargement 9 is of sufficient size to permit of withdrawal or insertion of the base extension 10 or 11 of either of the shoes 6 or 7 so as to position the shoes in a manner to permit of their being moved upwardly from the enlargement 9, into engagement with the 80 rails 5, as shown in Fig. 2.

It will be seen that the dove-tailed fit of the shoes 6 and 7 with the chair plate 3, serves most effectively to lock the shoes, by means of rigidly structural parts, against 90 upward displacement so that the said shoes will be capable of successfully resisting upward movement of the rails which may take place from contraction or following the release of the load as a train advances. 95

In order to provide for locking action of the shoes 6 and 7 against movement inwardly of the rails, I provide rigid means which may be in the form of a bar 12. The shoes 6 and 7 are provided with recesses 13 100 and 14 adapted to receive the ends of the bar 12, and also the shoes 6 and 7, are suitably apertured to receive bolts 15 and 16. Thus when the bar 12 is in position, as shown in Figs. 1 and 2, the shoes 6 and 7 105 will be rigidly locked against the inner sides of the rails 5, and the latter will be securely seated against the outer shoes 4.

While I have shown outer shoes having flange-engaging portions 17 and inner shoes 110 having flange-engaging portions 18 and 19, each also having a rail web-engaging por-

tion, I may in some constructions omit the web-engaging portions, especially at such points where the track is straight and where the tendency to spread the rails is less pronounced than on curved portions of the track. In Fig. 5, the web-engaging portion of the shoe 4 is indicated at 20, and in Fig. 6, the web-engaging portion of shoe 6 is indicated at 21.

10 It will thus be seen that I have provided a chair plate 3, which may, as shown, extend completely lengthwise of the tie so that one chair plate will serve for both rails, and in this connection, I desire to assert that irrespective of the character of the sleeper used, one of the novel features of the invention consists in a chair plate having a rigid shoe for engagement with one side of a rail and an adjustable shoe for engagement with the 20 other side of such rail.

While I have herein shown and described one specific embodiment of my invention, I do not wish to be limited thereto, except for such limitations as the claims may import.

25 I claim:—

1. A cross tie for railways comprising in combination, a U-shaped sleeper provided with laterally projecting flanges, a chair plate mounted on and secured to the flanges

of said sleeper and provided with rigid outer rail-engaging shoes and having longitudinally disposed dove-tailed ways formed therein, movable rail-engaging shoes having dove-tailed extensions adapted to fit said ways, and bar means for locking said movable shoes in engagement with said rails, substantially as described.

2. A railway cross tie, including a base of substantially U-shape cross section, a cover for said base extending substantially throughout the length thereof, said cover having rail-engaging shoes carried upon the ends thereof, said cover having a longitudinally disposed aperture therein, a portion of said cover being disposed adjacent the ends of said aperture to provide dovetail recesses, detachable rail engaging shoes insertible in said dovetail recesses to engage a rail, and a locking bar having its ends connected to each of said rail engaging shoes, as and for the purpose set forth.

In testimony whereof I affix my signature in presence of two witnesses.

THOMAS DAVIS.
